UNITED STATES PATENT OFFICE.

GEORGE E. SCHENCK, OF EAST RUTHERFORD, NEW JERSEY, ASSIGNOR TO CORA M. DAVIS, OF NEW YORK, N. Y.

REDUCING-CORSET.

1,274,457.

Specification of Letters Patent.

Patented Aug. 6, 1918.

Application filed January 31, 1916. Serial No. 75,381.

To all whom it may concern:

Be it known that I, GEORGE E. SCHENCK, a citizen of the United States, residing at East Rutherford, in the county of Bergen 5 and State of New Jersey, have invented certain useful Improvements in Reducing-Corsets, of which the following is a specification, reference being had therein to the accompanying drawing.

10 This invention relates to improvements in corsets, and more particularly to a reducing corset, one object of the invention being the provision of a corset, which when worn will reduce the size of the surrounded portions 15 of the body, and consequently the weight of the wearer.

As an additional object, the present invention contemplates the provision of a rubber corset wherein the body portion of 20 each of the main sections is composed wholly of rubber, novel reinforcing means being provided for the sections so that the corset may be employed in the same manner as an ordinary corset, thus obviating the employment 25 of a separate pair of corsets as is customary when using a reducer or rubber shield.

A still further object of the present invention is the provision of a corset of this character, which is simple, durable and inexpensive to manufacture, and which is useful and practical.

In the accompanying drawings:—

Figure 1 is a front elevation of the corset. 35 Fig. 2 is a rear elevation thereof.

Fig. 3 is a cross section on line 3—3 of Fig. 2, to show the method of securing the various stays and the attaching members in place.

40 Fig. 4 is an enlarged section showing the thickness of the various materials with one of the front fastening stays in place.

Referring to the drawings, the numerals 10 and 11, designate the two sections of the 45 corset, which may be made in styles of the day, and each section is composed of one or more sheets of pure medicated rubber 12, preferably three sheets overlying one another and attached by a cementing process.

50 Secured to the front of each section is a metal front stay 13 and 13', respectively, one of which is provided with headed studs 14, while the other has the eyes 15. Each stay is placed between folded portions of a strip 55 16 of rubberized fabric, and such strips are

secured to the edges of the sections 12 by cementing process to form casements. Thus the front edges of the members are reinforced and the proper attaching stays are held in place to be operated as in ordinary 60 corsets. At the rear edges of each member is attached the lace receiving metal stays 17 and 18, which are similarly connected in place.

Other strengthening ribs or stays 19 are 65 now provided and are formed preferably of whalebone, being mounted in fabric pockets 21, which in addition to supporting the stays, act as a reinforcement to the corset. These pockets are attached to the sheets 12 by a 70 cementing process, the outer surface being entirely covered by strips 22 of rubber. Wherever found desirable the duck reinforcement 23, may be employed, this being found necessary where garter or other 75 attachments are to be employed.

The reinforcements 16 are each provided with eyelets 24 below the metal stays, so that a lacing 25 may be placed therein for drawing the flexible ends closer together. 80

With this construction of corset, the same can be worn as a regular corset, and can also be worn by acrobats and the like, as the sections being elastic will permit free movement of the body. 85

Where so desired, eyelets 26 may be attached to the sections to thus permit ventilation, and reduce the perspiring action of a solid impervious covering upon the body.

Reinforcing bindings 27 are cemented or 90 otherwise engaged on the upper and lower edges of the sections.

It is to be noted that if desired medicated uncured rubber may be used and the various rubber parts secured in position by a pressing operation, thus obviating the employment 95 of the cementing process.

From the foregoing description taken in conjunction with the drawings, it is evident that a comfortable reducing corset that is 100 readily applied and worn, is provided.

What I claim, as new, is:—

A reducing corset composed of two sections the body portion of each of which is formed of pure laminated rubber, rubber 105 strips cemented at their marginal edges on the outer face of each body portion at spaced intervals and vertically thereof to form pockets, a fabric covered reinforcing stay mounted in each of the pockets, metal front 111

stays one of which is provided with hooks while the other is provided with eyes, casements of rubberized fabric surrounding the metal front stays and securing the front stays to the front edges of the sections, lace receiving metal stays, casements of rubberized fabric for connecting the lace receiving metal stays to the adjacent rear edges of

each section, a lace engaging through the receiving stays for connecting the sections together and reinforcing bindings cemented to the upper and lower edges of the sections and also covering the adjacent edges of the pockets and the casements. 10

In testimony whereof I affix my signature.
GEORGE E. SCHENCK.
